MULTIPLE LAYER STAY TAPE

Donald S. Bruce, Paul W. Herrlinger, and Howard L. Heise, Troy, Ohio, assignors to The Gummed Products Company, Troy, Ohio, a corporation of Ohio

Application August 15, 1950, Serial No. 179,622

1 Claim. (Cl. 154—53.5)

1

Our invention has to do with gummed tape and relates particularly to stay tape such as is used along the edges of boxboard cartons and the like to form corner joints. More specifically, our invention has to do with the provision of a multiple layer stay tape in which the individual layers of the tape are free of each other in the area which will bridge an angular edge of the carton to which the tape is applied.

In the manufacture of boxboard cartons, particularly shipping cartons made of corrugated board, it is customary to form the carton body by tubing a blank having four body walls in articulation. Cartons of this character are not provided with an attachment flap for tubing the body walls; but rather the body walls are tubed simply by bringing their free edges adjacent each other and applying over the adjacent edges a strip of stay tape, the tape being adhered to contiguous marginal portions of the adjoining wall panels. The tape may be applied when the tubular body is in flat condition, the walls being joined lying substantially coplanar with respect to each other and shipped to the user in knocked-down condition. However, there are instances wherein the tape is applied to the carton when it is in substantially set up condition, in which case the tape is folded longitudinally about the edge of the structure being sealed. Following erection of the carton, including the closure of its bottom, the contents are placed in the carton followed by the closing and sealing of the top closure.

It has been found that the contents of a carton will exert outwardly directed forces against the walls of the carton which, while they may not be sufficient to burst the walls of the carton, will at times be sufficient to split or burst the tape securing the edges of the wall panels to each other. This is particularly true in larger cartons having substantial volume; and even where the tape is reinforced, such as tape reinforced with spaced laterally extending threads, there is still a marked tendency to split or burst along the seam.

It is a principal object of our invention to provide a stay tape which is made up of a plurality of relatively thin layers of tape forming material and capable of withstanding the forces exerted against the edges of a carton to which it is applied.

It is an object of our invention to provide a multiple layer stay tape in which the layers are adhered to each other only along marginal edges, the intermediate areas of the layers being free to flex independently of each other. We thus

2

take advantage of the superiority in shock resistance and ultimate strength of a multiplicity of relatively thin, relatively free moving members as compared to an equal bulk of the same basic material in essentially unitary form.

It is a further object of our invention to provide a continuous process for the manufacture of multiple layer stay tape wherein a plurality of tape widths may be fabricated as a unit and thereafter severed into single tape width.

These and other objects of our invention which will appear hereafter or which will be apparent to one skilled in the art upon reading these specifications, we accomplish by those constructions and arrangements of parts of which we shall now describe certain exemplary embodiments. Reference is now made to the accompanying drawings wherein:

Figure 1 is a diagrammatic side elevation of means for applying spaced longitudinal stripes of adhesive to a sheet of tape forming material.

Figure 2 is a sectional view taken along the line 2—2 of Figure 1 and showing a cross sectional portion of the gummed web.

Figure 3 is a partial perspective of the wiper blade employed with the glue applying roller of Figure 1.

Figure 4 is a diagrammatic side elevation of a device suitable for forming multiple layer stay tape in accordance with my invention.

Figure 5 is an exploded view taken along the line 5—5 of Figure 4 and showing the three webs of tape forming material prior to their association with each other.

Figure 6 is similar to Figure 5 but illustrates the webs after they have been pressed together.

Figure 7 is a partial perspective view with parts stripped away showing a single width of tape.

Figure 8 is a cross sectional view of the strip of multiple layer tape illustrated in Figure 7.

Figure 9 is a partial perspective view of the tape applied to a boxboard carton.

Figure 10 is a sectional view taken along the line 10—10 of Figure 9 and illustrating in somewhat exaggerated fashion the action which occurs when the multiple layer tape is folded about an edge of a carton.

Figure 11 is a cross sectional view of an alternative form of multiple layer tape.

Figure 12 is similar to Figure 11 excepting the tape is in completed condition with its free ends adhesively secured to adjacent portions of the tape.

Referring now to Figure 1 of the drawings, the reference numeral 1 indicates a supply roll

of suitable tape forming material, which may be kraft paper, fabric or the like. A continuous web 2 of the tape forming material is withdrawn from the supply roll 1 and passed over glue applying means 3 where spaced longitudinal stripes of adhesive are applied to the web.

The glue applying means comprises a glue pot 4, transfer roll 5, wiper blade 6 and applicator roll 7. As will be explained more fully hereinafter, the adhesive applied to the web is preferably a thermoplastic adhesive and hence the glue pot 4 is provided with heating means 8.

The glue applying means is of a length equal at least to the width of the web being acted upon and the spaced stripes of adhesive are obtained by means of the wiper blade 6 which is indented in the manner illustrated in Figure 3, having scraping portions 9 and indented portions 10. The scraping portions 9 will be in contact with the glue applicator roll 7 and hence will scrape the adhesive from the roll in the areas which they contact, thus leaving stripes of adhesive only in the paths of the indented areas 10. The stripes of adhesive so formed will be transferred to the web 2 by the roller 7, as will be readily understood. The width of the glue stripes and their distance apart will be determined by the size of the individual tape widths being produced.

After passing the glue applying means, the web 2 is passed around a cooling or drying drum 11 which will solidify the stripes of thermoplastic adhesive applied to the web. The web is, of course, passed around the cooling drum with the stripes of adhesive to the outside. After passing around the cooling drum, the coated web is then wound on the storage roll 12.

The coated web produced by the above operation is illustrated in cross section in Figure 2, wherein the web is indicated at 2 and the longitudinal glue stripes are indicated by the reference numerals 13.

To form multiple layer stay tape, the procedure illustrated diagrammatically in Figure 4 of the drawings is next carried out. In the embodiment illustrated stock rolls 12 and 12a of adhesively coated tape forming material are provided, together with a roll 14 of plain paper or the like, depending upon the nature of material being used. Thus, there is provided an upper web 15 having adhesive stripes 16 on its lower surface, as can be seen in Figure 5, and a corresponding, lower web 15a having adhesive stripes 16a on its uppermost surface and facing the web 15. Between the webs 15 and 15a is the web 17 which is the plain web. The three webs are led together between the heated rolls 18 and 19 which serve to press together the webs 15, 17 and 15a, the heat of the rolls reactivating the thermoplastic adhesive stripes 16 and 16a thereby causing them to adhere to opposite sides of the plain web 17.

Following the joining of the webs 15, 15a and 17, the combined webs are passed around the cooling drum 20 which causes the thermoplastic adhesive to harden. After passing the cooling drum 20 the combined webs may then be wound on a storage roll 21.

The multiple layer produce is seen in partial cross section in Figure 6, the section illustrating a width comprising four widths of tape. To obtain the individual widths of tape, the webs are severed along the adhesive stripes along the lines a, b, c and d in Figure 6 to provide individual multiple layer strips. This may be done as a step in the continuous operation shown in Figure 4, or it may be done separately. One of

the severed strips can be seen in Figures 7 and 8. It will be noted that the layers are adhered to each other along their longitudinal edges but that intermediate these edges, i. e. the central or median area of the tape layers are free of each other. As seen in Figures 7 and 8, a coating of ordinary tape gumming 22 is applied to an outermost layer of the tape so that it may be adhered to a contacted surface. The coating of tape gumming 22 may also be omitted centrally of the tape so that the layer of tape material to which the gumming is applied will also be free to flex intermediate its edges.

While we have described our invention in terms of a tape made up of three layers or plies of tape forming material, it will be understood that two, three, four or even more layers may be provided without departing from the principle and spirit of our invention. Where more than two layers are employed, it is essential, however, that the glue stripes be in alignment with each other so as to maintain the proper free area centrally of the combined layers.

The adhesive employed to join the layers or webs of tape forming material together is preferably a thermoplastic adhesive which can be readily reactivated when the tape forming webs are combined. Of course, a water activative adhesive may be used if so desired, but such adhesives require application to the webs immediately prior to the joinder of the webs, or else require the provision of means ahead of the combining rolls to wet the adhesive.

The specific nature of the thermoplastic adhesive employed may be varied widely and there are numerous substances known to the art which will be suitable to combine the layers. We prefer, however, to employ a thermoplastic adhesive which is insoluble in water, such as wax, rosin, polyamide or polyvinyl acetate adhesives. Such adhesives have the ability to resist being wetted by water and hence will not be affected when the gummed tape, such as 22 in Figure 8, is moistened prior to the application of the tape to a carton being sealed.

In Figure 9 a section 23 of the multiple layer tape is shown adhered over the meeting edges of walls 24 and 25 of the carton 26. A cross-sectional view of the tape associated with the carton 26 is shown in Figure 10 greatly enlarged. It will be apparent from Figure 10 that the outermost layers of the tape are stretched about the corner whereas the innermost layer is simply folded about the corner of the carton. The tape layers, being unadhered to each other in the area along the edge of the carton, flex independently of each other and this has been found to greatly increase the shock resistance and ultimate strength of the tape.

The use of multiple tape layers, as noted, gives a decided increase in the strength characteristics of a given weight of tape forming material. By way of example of two sheets of kraft paper of 34 and 57.5 lb. basis weights (24 x 36—500 sheets) gave individual Mullen or bursting strength readings of 35 and 58 lbs. per sq. in., respectively, for a total of 93 lbs. per sq. in. Tested together in the form here disclosed, this two sheet combination resulted in a bursting value of 100 per sq. in. By contrast a single sheet of kraft of identical type having a basis weight of 91.5 lbs. or equivalent to the combined basis weights of the 34 and 57.5 lb. sheets gave a bursting strength of 83 lbs. per sq. in. Thus by the combination we not only show an improvement over

the sum of the individual sheets but achieve an improvement in bursting strength of approximately 20% over the single sheet.

As a second example, three sheets of kraft of 34.3, 50 and 58 lbs. basis weight show individual bursting strengths of 38, 47 and 60 lbs. per sq. in. for a total of 145 lbs. per sq. in. Tested together these same sheets show a bursting strength of 153 lbs. sq in. By contrast a single sheet of kraft of identical type having a basis weight of 142 lbs. or essentially equivalent to the compared basis weights of 34.3, 50 and 58 lb. sheets gave a bursting strength of 109 lbs. per sq. in. Thus again by the combination we achieve an improvement in bursting strength this time approximately 40% over the single sheet of essentially equal weight.

In Figures 11 and 12 we have shown an alternative construction in which the multiple layer tape is made from a single width of tape-forming material which is folded and reversely folded to provide several layers of the finished tape. Referring to Figure 11, a sheet of tape-forming material 27, coated on one surface with a water sensitive adhesive 28, is folded so as to provide the layers 29, 30 and 31 and the flap portions 32 and 33. In the illustrated embodiment, the adhesive 28 lies outermost of the layer 31 and innermost of the layer 29. Thus the adhesive will cover the outside portion of the flap 33 but the flap portion 32, will, as to its external surface, be uncoated. However, by applying water as indicated at 34 and 35, and thereafter pressing the layers 29, 30 and 31 together, the flaps 32 and 33 will be adhered to adjacent portions of the layer 30 and hence join the three layers together along their outermost edges, as illustrated in Figure 12. The result is again a product in which the individual layers are secured to each other along their longitudinal edges and yet free to flex intermediate the edges.

Modifications may, of course, be made in our invention without departing from the spirit of

it, and we do not intend to be limited to the specific embodiments illustrated in any manner other than as expressed in the claim which follows.

Having thus described our invention in certain exemplary embodiments, what we desire to secure by Letters Patent is:

A continuous strip of multiple layer stay tape for application to the edges of adjacent panels of box-board cartons to form joints, comprising a plurality of plies of kraft paper of about 34 to about 60 pounds basis weight, said plies being of equal width and superposed one on the other with their adjacent longitudinal edges defining a common plane, marginal edge portions only of said plies being permanently secured to each other by laterally spaced stripes of adhesive extending lengthwise of the tape, the areas of said plies lying between said marginal edge portions being free of adhesive and non-adhering and capable of being flexed with respect to each other, said plies being disposed throughout the area thereof in substantially flat, juxtaposed face to face relation, whereby said tape may be continuously wound in a tight roll on an axis transverse to the length of the tape.
